UNITED STATES PATENT OFFICE

JAMES V. MARTIN, OF GARDEN CITY, NEW YORK

DESIGN FOR AN AUTOMOBILE BODY

Application filed December 6, 1929. Serial No. 33,677. Term of patent 14 years.

To all whom it may concern:

Be it known that I, JAMES V. MARTIN, a citizen of the United States, residing at Garden City (Martindale), in the county of Nassau and State of New York, have invented a new, original, and ornamental Design for an Automobile Body, of which the following is a specification, reference being had to the accompanying drawing, forming part thereof.

Figure 1 is a front and side elevational view showing my new design in perspective.

Fig. 2 is a top plan view of the automobile body of my design.

I claim:

The ornamental design for an automobile body, as shown.

JAMES V. MARTIN.
